Geo. P. Kimmel.
ATTORNEY.

UNITED STATES PATENT OFFICE

HELEN BARNES, OF BUTTE, MONTANA

COMBINED INKWELL AND PENHOLDER

Application filed May 21, 1929. Serial No. 364,842.

This invention relates to a combined inkwell and pen support, and has for its object to provide, in a manner as hereinafter set forth, an article of such class with a support for maintaining a pen and its holder at an angularly disposed, upright position in convenient reach of a person and further whereby the pen point is submerged in the ink in the well when the support maintains the pen holder in angular, upright position.

A further object of the invention is to provide, in a manner as hereinafter set forth, an article of the class referred to with a tubular support for a pen and its holder, and with the support having means for wiping off the surplus ink from the pen when the latter is withdrawn from the support.

A further object of the invention is to provide, in a manner as hereinafter set forth, an article of the class referred to including a storage and a delivery ink reservoir communicating with each other, and adjustable means operating in the storage reservoir for displacing the ink therein to control the level of the ink in the reservoirs.

A further object of the invention is to provide, in a manner as hereinafter set forth, an article of the class referred to including a storage and a delivery reservoir for ink, and further including a tubular support for a pen holder and with the support permanently opening into the delivery reservoir.

A further object of the invention is to provide, in a manner as hereinafter set forth, an article of the class referred to including storage and delivery reservoirs receiving its supply from the former and with the article so constructed as to permit of one visibly ascertaining the level of the ink within said reservoirs.

Further objects of the invention are to provide, in a manner as hereinafter set forth, an article of the class referred to which is simple in its construction and arrangement, strong, durable, pleasing in appearance, thoroughly efficient in its use, conveniently assembled, and comparatively inexpensive to manufacture.

With the foregoing and other objects in view the invention consists of the novel con-

struction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a combined ink well and pen support in accordance with this invention.

Figure 2 is a section on line 2—2 Figure 1.

Figure 3 is a section on line 3—3 Figure 1.

Figure 4 is a vertical sectional view of the article taken through a pen support.

Figure 5 is a sectional plan of the pen support on line 5—5, Figure 4.

A combined ink well and pen support in accordance with this invention includes an ink holding element, a pen supporting element and an ink displacing element. The pen supporting element is connected to and disposed at an angle with respect to the ink holding element. The ink displacing element is adjustably connected to and disposed at an angle with respect to the ink holding element. The pen supporting and ink displacing elements project a substantial distance above the ink holding element.

The ink holding element may be of any suitable contour, preferably rectangular and is so shown. The ink holding element is constructed in a manner so that one can readily ascertain the level of the ink therein, or in other words, is so formed that the level of the ink therein will be visible. The ink holding element is formed of two sections suitably secured together and arranged in superposed relation. Preferably the top section is formed of transparent material and the bottom section of opaque material and is so illustrated.

The ink holding element comprises an upper or top transparent section and a lower or bottom opaque section indicated generally at 1 and 2 respectively, and each of these sections is of rectangular contour. The sides and ends

of one section are flush with the sides and ends of the other section. The sections are secured together by a suitable cementitious material, as indicated at 3. The section 1 at its top is 5 beveled at its sides and ends as indicated at 4, 5 respectively.

The lower face of the section 1 is formed with a lengthwise extending recess, preferably of oval form, and indicated at 6. The 10 lower face of section 1 is furthermore provided with a circular recess 7 of a diameter materially less than the length of the recess 6 and the recess 7 is arranged at one side of the transverse median of recess 6, as well as 15 being substantially spaced from the former.

The lower face of section 1 is also provided with a vertically disposed groove 8 of less height than the recess 6 or 7 and which establishes communication between such recesses.

The upper face of section 2 is formed with a recess 9 which corresponds in contour to and is arranged in alignment with recess 6. The upper face of section 2 is also provided with a recess 10 of the same contour as and 25 which aligns with the recess 7. The upper face of section 2 is furthermore provided with a vertically disposed groove 11 of the same height as the height of the recesses 9 and 10 and which aligns with the groove 8. The cementitious material 3 forms continuations of the walls of said recesses and grooves and in connection with the recesses 6 and 9 provide a storage reservoir 12, in connection with the recesses 7 and 10 form a delivery reservoir 25 13 and in connection with the grooves 8 and 11 provide a feed passage 14 for the ink from the reservoir 12 to the reservoir 13. The reservoir 12 is of materially greater capacity than the reservoir 13.

The section 1 is formed with a vent opening 14 for the reservoir 12. The section 1 is provided with an angularly disposed opening 15 which extends from the top of such section and opens into the reservoir 13. The upper 40 face of the section 2 is formed with a groove 16 having its wall forming a continuation of the wall of the opening 15. The cementitious material 3 also forms a continuation of the walls of the opening 15 and groove 16. A portion of the wall of the opening 15 is 45 threaded as indicated at 17.

The pen supporting element indicated generally at 18 comprises a tubular body 19, open at each end and having its outer end flared as at 20. The inner end of the body 19 is beveled and is flush with the wall of the recess 13. The body 19 is provided for a portion of its length with peripheral threads for engagement with the threads 17 whereby 50 the pen supporting element 18 is secured to the top section 1.

The element 18 opens into the reservoir 13 and is provided adjacent its inner end edge with a peripheral groove 21 having inclined walls and with the inner wall of such

groove provided with spaced openings 22 in which seat globular ink removing members 23 projecting into a passage 24 provided by the element 18. The pen and pen holder, not shown, is extended into the element 18 and the latter maintains the pen holder in an upright, angular position within easy reach of a person so that the pen holder can be removed when desired. The pen point carried by the holder extends into the body of ink 25 within the reservoir 13. The globular members 23 act to remove the surplus ink from the pen when the latter is withdrawn from section 1. The flaring outer end 20 of the element 18 facilitates the entrance of the pen and pen holder into the supporting element 18.

The ink displacing element is referred to generally at 26 and it comprises a threaded rod 27, provided at its outer end with a head 28 and at its inner end with an ink displacing member 29. The section 1 is formed with an angularly disposed opening 30 having a threaded wall with which adjustably engages the element 26. The element 26 extends into the reservoir 12 at a point in proximity where the passage 14 communicates with reservoir 12. The elevating and lowering movement of the element 26 will provide for changing the level of the ink 10 within the reservoirs 12 and 13, under such conditions when it is desired the level of the ink within reservoir 13 can be raised. The head 28 provides for the convenient rotating of the element 26.

It is thought the many advantages of a combined ink well and pen support in accordance with this invention and for the purpose set forth can be readily understood, and although the preferred embodiment of the invention is as illustrated and described, yet it is to be understood that changes in the details of construction can be had which fall within the scope of the invention as claimed.

What I claim is:

1. An inkwell comprising a body portion formed of a pair of superposed sections secured together, each section having its inner face provided with a pair of spaced recesses and a groove connecting the recesses, the recesses and groove of each section being spaced from the sides and ends of the section, the recesses and groove of one section coating with the recesses and groove of the other section to provide within said body portion an ink storage reservoir, an ink delivery reservoir and a passage for establishing communication between the storage and delivery reservoirs, said upper section formed with a vent for said storage reservoir, said body formed with an inclined opening leading from one side of the delivery reservoir through the upper body section to the top of said body for access to the delivery reservoir, and an adjustable inclined ink expelling

means threadedly engaging directly with and extending through the upper body section into said storage reservoir and projecting outwardly from the top of said body portion.

- 5 2. A combined pen holding and surplus ink removing attachment for that type of inkwell having an enclosed ink delivery reservoir and an inclined opening leading from said reservoir to the top of the ink well, the wall of said opening being threaded for a portion of its length, the combination of a pen holder receiving member of tubular form for mounting in and of greater length than said opening, said member having a portion of its outer periphery plain and a portion threaded, the said threaded portion of said member engaging with threads of said wall, the inner end of said member being flush with the inner end of the opening, the outer 20 end of said member projecting from the inkwell and flared, said member having an annular groove in the plain portion of its outer periphery between its inner end and said peripherally threaded portion, the wall of 25 said groove formed with spaced openings, and freely movable surplus ink removing elements of globular form seated in said openings and extending inwardly of the inner face of said member.
- 30 3. A combined pen holding and surplus ink removing attachment for securing to an inkwell comprising the combination of a tubular member having a flaring outer end portion and a bevelled inner end, said member having an annular groove in its outer periphery in proximity to said inner end, the wall of said groove being formed with spaced openings, and surplus ink removing elements of globular form seated in said openings and extending inwardly of the inner face of said member, said elements being freely movable.
- 40 4. A combined pen holding and surplus ink removing attachment for securing to an inkwell comprising the combination of a tubular member having a flaring outer end portion and a bevelled inner end, said member having an annular groove in its outer periphery in proximity to said inner end, the wall 45 of said groove being formed with spaced openings, and surplus ink removing elements of globular form seated in said openings and extending inwardly of the inner face of said member, said elements being freely movable, said member having peripheral threads intermediate its ends for securing it to an inkwell.

In testimony whereof, I affix my signature hereto.

HELEN BARNES.
